PIANO

Louis Heitzmann, Long Island City, N. Y., assignor to Harry J. Schmer, New York, N. Y.

Application February 24, 1933, Serial No. 65,214

7 Claims. (Cl. 84—840)

This invention relates to pianos and has to do more particularly with the key-operated mechanism in an upright piano, an object of the invention being to provide an improved construction and arrangement of the parts of such mechanism, which will be extremely compact and will render it possible to considerably reduce the height of an up-right piano without impairing its operation.

Other objects and advantages of the invention, as well as the novel details in the construction, arrangement and combination of the parts, will become apparent from a study of the following description, when taken in connection with the accompanying drawing in which Fig. 1 is a side elevation of an up-right piano action and key lever arrangement embodying my invention, the several parts thereof being in their normal or at-rest position; Fig. 2 is a similar view, showing the parts in the position which they assume after a key has been struck and when in check; Fig. 3 is a top view of the inner end portion of the associated key lever; Fig. 4 is a top view of the inner end portion of the key lever showing a modified form of the invention and Fig. 5 is a side elevation of the parts shown in Fig. 4.

Referring more particularly to the drawing, the reference character 1 indicates the inner end of a piano key lever which is supported intermediate its ends upon a block 2 mounted on the base board 3 of the piano. The key lever is pivoted to rock on the block 2 in the customary fashion by means of a pin 4, which extends up through the key lever. A cushion 5 of felted material is provided on the base board 3 to support the inner end of the key lever in its normal or at-rest position as shown in Fig. 1.

Intermediate the inner end of the key lever and the associated piano wire 6, is disposed the action mechanism comprising a wippen 7, pivotally supported at 8 by a depending flange 9, which is secured at its upper end to the lower end of an action rail 10. Fastened to the upper end of the action rail 10 is a flange 11 pivotally supporting a hammer-butt 12, which carries the usual shank 13 and the hammer 14, the shank 13 resting against the rail 15 when in its normal or at-rest position, as shown in Fig. 1. The hammer-butt 12 is provided with the usual cushion 16 and the upwardly and outwardly inclined cushion surface 17. The cushions 16 and 17 are engaged by the upper offset end 18 of a jack 19, which is pivoted at its lower end to an upwardly extending lug 20, carried by the wippen 7. The offset end 18 of the jack is normally held against the cushion 16 and 17 and in the corner formed by said cushioned surfaces by a spring 21, which is positioned between an outwardly extending arm 22 formed at the lower end of the jack and the upper surface of the wippen, as shown in Fig. 1. Just above the arm 22 is supported a stop 23 with which the arm 22 is adapted to contact during the upward movement of the wippen under the action of the piano key. It will be evident that as soon as the arm 22 engages with the stop 23, the upper end 18 of the jack 19 will begin to swing outwardly and to move along the cushioned surface 17, the upward movement of the jack as it is lifted by the wippen rail 7 forcing the hammer-butt 12 about its pivot and causing the hammer 14 to strike the piano key. In standard up-right piano actions the stop 23 is usually an individual regulating button which is supported on a stop rail suitably mounted in the piano and may be adjusted to regulate the let-off of the hammer from the string.

To the hammer-butt is connected a downwardly and outwardly extending inclined rod or screw 24, which carries a counter-check or button 25 on its outer end. The screw 24 extends through a slotted arm or back-check 26 provided on the jack 19 near its upper end, said arm being disposed in angular relation with the offset end 18 of the jack and extending upwardly and outwardly from the jack to a point beyond the rod 24 or screw 24, which carries the button 25. Thus, when the jack 19 is actuated as above described to operate the hammer, the outer face of the arm or back-check 26 will contact with the button 25, thereby stopping the movement of the hammer and holding it against vibration, as shown in Fig. 2. The parts are so arranged that the locking action will not take place until the hammer 14 has struck the string 6 a blow. Due to the inclination of the back-check 26, it will start the hammer on its movement toward the rail 15 when the key is released independent of the spring 27, which is carried by the spring rail 28 and is adapted to return the several parts of the action to their normal or at-rest position.

As shown in Figs. 1 and 2, the wippen 7 is provided at its outer end with a pair of spaced downwardly-extending projections or lugs 30, which form a support for a pin 31, which extends transversely therethrough. Pivottally connected to the pin 31 intermediate the lugs 30 is the short leg 32 of a bent pull rod or wire, the longer leg 33 of which is disposed at right angles to the short leg 32 and extends upwardly in a vertical direction intermediate the outer end of the wippen 7.

pen 7 and the inner end of the key lever 1. The upper end of the longer leg 33 passes through a slot formed in the inner end of the key lever 1, which projects sufficiently beyond the inner end 5 of the base board 3 and the cushion 5 to provide for free movement of the pull rod. As shown more clearly in Fig. 1, the slot extends the width of the projecting end of the key lever 1, which is beveled downwardly and outwardly to form the 10 curved end surface 34 of the key lever, said slot being constricted at its outer end by a pair of beads 35, as shown in Fig. 3. The beads 35 and the end surface 36 of the slot diverge downwardly so that a substantially frusto-conically 15 shaped opening 37 is formed in the projecting end of the key lever through which extends the upper end portion of the pull wire. The walls of the slot are provided with a cushion 38, as shown more clearly in Figs. 1 and 3. The upper end 20 portion of the long leg 33 of the pull wire is screw-threaded and carries a button 39, which rests on the upper surface of the key lever 1. The pull wire 32, 33 must, of course, have a rigidity appropriate to maintain the angular 25 relation between the leg 32 and the leg 33 at the end of each operation. At the same time the presence of the angle in the pull wire introduces into the structure a certain elasticity which contributes to the so-called touch of the instrument. For example, when the key is depressed 30 in playing the piano, a tendency to open the angle ensues, but the resilient reaction of the legs of the pull wire to maintain the angle there-between will impart a follow-up impulse to the 35 wippen so that there will not only be a smart advance of the hammer against the string, but after the hammer butt 12 has moved away from the end 18 of the jack 19 there will be no active 40 force to counteract the upward elastically induced movement of the short leg 32 of the pull wire during the time that the original angle between the two legs of the pull wire is restored by the elasticity of the bent wire. It is further of 45 the same importance that the pivotal connection between the leg 32 and the pin 31 of the wippen be produced by a circular configuration of the end of the leg 32 since by this arrangement the fractional forces which would otherwise be opposed to the elasticity of the wire in regaining its initial angle as between legs 32 and 33, are reduced to a negligible minimum.

It will be seen that by reason of the above described arrangement of the parts, I am enabled 55 to position the action mechanism intermediate the inner end of the key lever and the piano wire and thereby considerably reduce the height of the standard up-right piano, without affecting the normal operation of such mechanism. When the 60 piano key is depressed, the key lever 1 will rock about its pivot, thereby raising the inner end thereof, which motion will be transferred to the wippen 7 by means of the pull rod so that the hammer 14 will be caused to strike the string 6. Due to the manner in which the pull rod is 65 connected to the key lever and the wippen, the movement of the parts will be entirely free, unrestrained and noiseless. By adjusting the button 39, the standard depth of touch can be accurately 70 obtained.

In the modified form of the invention shown in Figs. 4 and 5, the inner end of the key lever is provided with an outwardly extending vertical slot 40 provided with straight parallel side walls 75 and having a cylindrically-shaped inner por-

tion 41, through which extends the longer leg 33 of the pull rod or wire. The upper end of the slot portion 41 is countersunk to form a recess 42 within which is seated a relatively long button 43 having a diameter less than that of the recess 5 10 to prevent frictional contact therebetween during the operation of the parts. The button 43 is provided at its lower end with a felt disc 44 having a diameter substantially equal to that of the recess 42 so that it fits snugly in the bottom 15 end of such recess. The advantages of this construction over the construction shown in Figs. 1 to 3 are that it is less expensive, positively maintains the leg 33 of the pull rod in proper relation to the slot, yet enables the pull rod to be 15 readily disconnected from the key lever and reduces friction to a minimum.

It will be apparent that other modifications may be made in the construction and arrangement of my invention without departing from 20 the scope thereof as covered by the appended claims, whose purpose it is to include and embrace any such modifications or equivalents.

I claim:

1. In an up-right piano, the combination of a 25 string, a pivoted key lever extending outwardly to the front of the piano, and action mechanism disposed intermediate said string and the inner end of said key lever and in operative association with said string and key lever, said 30 mechanism comprising a wippen located below the level of said key lever, means for pivotally supporting said wippen, and a pull wire pivotally connected to the outer end portion of said wippen and extending thence first toward the front of 35 the piano and then upwardly through a slot provided in the inner end of said key lever, said slot being formed to enable the pull wire to move freely throughout its range of movement, an adjustable button carried by said pull wire and 40 seated upon the inner end of said key lever and means for retaining the pull wire in proper position in said slot.

2. In an up-right piano, the combination of a 45 base board having a stationary pivot mounted thereon, a key lever fulcrumed on said pivot and extending inwardly towards a piano string, the inner end of said key lever projecting beyond the inner end of said base board, action mechanism disposed intermediate the inner end of said 50 key lever and said string, said mechanism comprising a wippen located below the level of said key lever, means for pivotally supporting said wippen, and a pull wire connecting said key lever with said wippen, said pull wire comprising 55 an offset lower end portion pivotally connected to the outer end portion of said wippen and a main portion which extends upwardly at an approximately right angle to the offset portion between said action mechanism and the 60 inner end of said base board and passes through a slot provided in the inner projecting end of said key lever, said slot being formed to enable the pull wire to move freely throughout its 65 range of movement, an adjustable button carried by said pull wire and seated upon the inner projecting portion of said key lever and means for retaining the pull wire in proper position in said slot.

3. In an up-right piano, the combination of a 70 string, a pivoted key lever extending outwardly to the front of the piano, the inner end of said key lever being slotted to provide a pair of inwardly extending vertically disposed flanges, action mechanism disposed intermediate said string and 75

- the inner end of said key lever, said mechanism comprising a wippen located below the level of said key lever, means for pivotally supporting said wippen, and a pull wire connecting said key lever with said wippen, said pull wire comprising an offset lower relatively horizontal end portion pivotally connected to the underside of the outer end portion of said wippen, and a main portion which extends upwardly in a relatively vertical direction and passes through the slot in said key lever, an adjustable button carried by said pull wire and seated upon the inner end of said key lever and means for retaining the pull wire in proper position in said slot.
- 15 4. A piano such as set forth in claim 3, in which the flanges on the inner end of said key lever are provided with beads to constrict the side opening of said slot, said beads and the inner side of said slot diverging downwardly to provide a frusto-conically shaped opening for said pull wire and cushion material lining the inner walls of said slot.
- 5 5. A piano such as set forth in claim 3, in which the root portions of said inwardly extending flanges are thinner than the outer portions thereof, to provide an enlarged section of
- the slot between such flanges and are provided with a counter-sunk recess arranged coaxially with the enlarged section of the slot, said adjustable button being seated in said recess and comprising a body portion having a cross-sectional area less than that of said recess and a cushioning member fastened to the lower end of said body portion and having an area substantially equal to the cross-sectional area of said recess.
6. The combination set forth in claim 1 in which the pivotal supporting means between the wippen and the pull wire comprises a circular configuration at that end of the pull wire which forms the pivotal connection with the wippen, and a pin associated with the wippen and normally extending through and supported against said circular end portion of the pull wire.
7. The combination set forth in claim 1 in which the slot at the inner end of the key lever is wider than the diameter of the pull wire and in which the means for retaining the pull wire within the said slot are constituted of a recess in the top portion of the end of the key lever within which recess is positioned the adjustable button.
